United States Patent Office

Des. 232,527
Patented Aug. 27, 1974

232,527

MEASURING CONTAINER

Harrison W. Sears, Deerfield, Ill., assignor to
Abbott Laboratories, North Chicago, Ill.

Filed June 14, 1972, Ser. No. 262,864

Term of patent 14 years

Int. Cl. D10—04

U.S. CL. D10—96

FIG.1

FIG.2

FIG.3

FIG.4

FIG.5

FIG. 1 is a perspective view of a measuring container showing my new design;

FIG. 2 is a front elevational view thereof;

FIG. 3 is a rear elevational view thereof;

FIG. 4 is a top plan view;

FIG. 5 is a side elevational view thereof, the opposite side being identical thereto.

I claim:

The ornamental design for a measuring container, substantially as shown and described.
